UNITED STATES PATENT OFFICE.

CARL WALTHER, OF CHEMNITZ, GERMANY.

SPEED-RETARDING DEVICE FOR THREAD-GUIDE BARS.

1,023,694.

Specification of Letters Patent. Patented Apr. 16, 1912.

Application filed March 25, 1911. Serial No. 616,982.

To all whom it may concern:

Be it known that I, CARL WALTHER, a subject of the German Emperor, residing at Chemnitz, in the Kingdom of Saxony and

5 Empire of Germany, have invented certain new and useful Improvements in Speed-
Retarding Devices for Thread-Guide Bars, of
which the following is a specification.

10 In many cases in the construction of ma-
chines it happens that a heavy object con-
tinually moves to and fro on a rectilineal
way. If this object at the end of its course
runs against a stationary body a serious
15 shock is caused and consequent damage re-
sults to one or both bodies.

The purpose of the present invention is
to avoid this violent contact of parts by re-
tarding the speed of the moving element in
the last moment of its motion.

20 In the accompanying drawing an instance
of the construction of the invention in a
straight knitting frame is fragmentarily
illustrated.

The object which is moved to and fro,
25 and whose movement is to be retarded at
the end of its traverse, is the thread guide
bar of a knitting machine 17, to which the
thread guides 11 are fixed. As is known
the thread guide 11 must be continually
30 shifted to and fro in the two directions in-
dicated by x and y . In the last moment of
the motion the rod 17 runs with the right
end against the cap 33 of the screw 13, and
in its reverse movement its left end strikes
35 the cap of the screw 13'. But because, as is
known, a knitting frame is very long, the
left end of the mechanism could not be illus-
trated in full in the drawing.

The stationary parts of the frame of the
40 machine are designated in the drawing by
the numerals 1, 2, 3. In the bearings 6, 7,
8 of which the bar 9 which is the slur bar of
a knitting machine can be shifted to and fro
in the directions indicated by the arrows x ,
45 y . The parts 14 are fixed to the bar 9, of
which in the drawing only one is illustrated.
The bar 15 is fixed to the arm 14. The bar
15 must therefore make exactly the same
motions as the reciprocating bar 9 which has
50 a constant traverse.

On the bar 15 rests a friction box 16,
which is not rigidly connected with the bar
15, but sticks so fast on the bar 15, that it
is taken along with it by friction. Only if
55 the friction box 16 is held fast will the bar
15 be able to continue to move alone. From

the friction box 16 an arm 18 extends up-
ward which engages a catch 29, which is
rigidly fixed to the bar 17. If the bar 9,
therefore, is moved to and fro in the direc- 60
tions x , y , this motion is transferred to the
rod 17 by the parts 15, 16, 18. But if the
bar 17 has a variable movement, it encoun-
ters the stop 33, the friction box 16 then
slips on the rod 15, and the bar 9 can con- 65
tinue to move.

The difference between the arrangement
known hitherto and the new invention is
essentially founded on the fact, that the
arm 18 and the slide 16 hitherto formed a 70
single rigid piece, whereas a new mecha-
nism 12, 19, 20 is now provided, which serves
for retarding the motion of the rod 17 at
the end of its run, and is described as fol-
lows. The slide 16 is provided with two 75
loops 26, in which the slide-bar 20 is mov-
able to and fro. The friction box 16 is fur-
nished with a journal 12, in which the rock-
ing crank lever 18 can swing. The crank
lever 18 is furnished with a pin 19, which 80
engages the curve-shaped slot 27 of the
slide-bar 20. To the right and to the left
of the slide-bar 20 are arranged two rods
24, 25. If the slide 16 is moved to and fro
in the direction of x , y , the slide bar 20 runs 85
against the rod 24 to the left, and against
the rod 25 to the right.

The screw 13 is adjustably fixed to the
arm 32. The arm 32 and the rod 25 are 90
fixed to a nut 31.

The mode of operation of the described
mechanism is as follows. If the bar 9 is
moved in the direction x to the right, the
slide-bar 20 runs against the rod 25. The
friction box 16 still continues to move with 95
the same speed as the bar 9. But because
the slide-bar 20 stands still, the pin 19
moves along the curve-shaped groove 27,
and the lever 18 holds back the bar 17.
The speed of the bar 17 is therefore retard- 100
ed in this way. If the bar 17 runs with a
very slow motion against the cap of the
screw 33, the friction box 16 will slide on
the bar 15, but the bar 9 will still continue
to move. 105

Having now described my invention and
in what manner the same is operated, what
I claim is:

1. In a knitting machine, knitting devices
including a reciprocating driver bar having
a constant traverse, a thread guide bar,
stops for said bar, means to vary the posi- 110

- tion of said stops to vary the strokes of said bar, a friction driven slide for reciprocating said guide bar from said driver-bar, a movable connection between said slide and said 5 guide bar, and an additional stop carried by said stop carrying means to adjust said connection to permit the bar to lag behind the slide when the guide bar approaches the end of its traverse.
- 10 2. In a knitting machine, a slur bar having a constant reciprocating movement, a post on said bar, a horizontal bar carried by said post, a friction box on said horizontal bar, a slide bar 20 having a curved slot, a

crank lever journaled in said friction box 15 whose lower end carries a pin engaged by said curved slot, a thread guide bar, a catch thereon engaged by the upper arm of said crank lever, an adjustable stop for said thread guide bar mounted on a nut movable 20 on a fashioning screw and another stop on said nut to limit the movement on said bar 20.

CARL WALTHER.
